UNITED STATES PATENT OFFICE.

HENRY D. MIX, OF PROVIDENCE, RHODE ISLAND, ASSIGNOR TO WIGHTMAN & HOUGH COMPANY, OF PROVIDENCE, RHODE ISLAND, A CORPORATION OF RHODE ISLAND.

CIGARETTE-HOLDER.

1,170,090.

Specification of Letters Patent.

Patented Feb. 1, 1916.

Application filed January 22, 1915. Serial No. 3,685.

To all whom it may concern:

Be it known that I, HENRY D. Mix, a citizen of the United States, and resident of the city of Providence, in the county of 5 Providence and State of Rhode Island, have invented certain new and useful Improvements in Cigarette-Holders, of which the following is a specification.

This invention has for its object to provide a holder for receiving and supporting a series of cigarettes side by side with their transverse major axes substantially parallel with each other and obliquely with respect to the medial line between the holder members, whereby instead of setting edge to edge the body portions of the cigarettes are caused to over-lap each other for the purpose of reducing the length of a holder designed to receive a given number.

20 A further object of this invention is to hinge the holder members together and cause them to grip and support their contents by spring pressure.

With these and other objects in view, the 25 invention consists of certain novel features of construction, as will be more fully described, and particularly pointed out in the appended claims.

In the accompanying drawings: Figure 30 1— is a perspective view of a cigarette casing in open position in which is mounted a holder of my improved type for supporting the cigarettes in an over-lapping position. Fig. 2— is a perspective view showing one 35 of a pair of holder members as being fluted. Fig. 3— shows a pair of holder members as hinged together and acted upon by springs to hold them normally in closed position to lightly bind the cigarettes when positioned 40 therein. Fig. 4— is an edge view of the holder showing the staggered relation of the opposite ribs and grooves for causing the body portion of the cigarettes to overlap each other. Fig. 5— is a section on line 45 5—5 of Fig. 3 showing a portion of a pair of fluted holders.

In order that my present invention may be more clearly understood, it should be explained that the natural form of a cigarette, 50 when finished, is oblong or oval in cross section so that each cigarette has both a major and a minor transverse axis and when the cigarettes are placed in a casing edge to edge or with their major axes in line, the 55 holder will be necessarily longer than when

the cigarettes are placed side by side, or with their minor axes in line, and when located in the latter position a casing or holder for the cigarettes is necessarily thicker than is desirable. Therefore, in 60 order to reduce the thickness of the casing or holder and also reduce its length to the minimum for receiving a given number of cigarettes, it is found very desirable to so place the cigarettes in the holder that their 65 major transverse axes will lie obliquely to the medial line through the holding members in which position the bodies of the cigarettes lie against and over-lap each other, whereby the greatest number may be placed 70 in the smallest possible space.

One form of holder for obtaining the desired result above described is illustrated in the accompanying drawings, in which—

11 and 12 designate the two holder members which are preferably hinged together as at 13, each member having its side wall 14 stamped or pressed or otherwise formed into a series of flutes or corrugations 15 for the reception of the cigarettes a. In order 75 to obtain the staggering effect of the grooves in the opposite members, in a simple and practical way, I have turned outwardly or opened the end wall 16 of one of the end flutes of each member so as to spread this 80 groove wider than the others, whereby the two opposite members may be formed by the same die and when reversed end for end upon each other the flutes will not register 85 but will be out of transverse alinement with 90 each other, giving to them a staggering effect, whereby when the cigarettes are placed therein the transverse major axis of each is obliged to set obliquely to the medial line 95 between these members.

The lower edge 17 of each member is turned inward forming a bottom portion against which the end of the cigarette rests when in its socket and the upper edge 18 of each member is turned outward slightly to 100 provide a suitable finish for the same. in practice it is found desirable to hinge these members together so that they may be opened somewhat to receive the cigarettes more readily, and it is also found advisable 105 to provide a slight spring or tension on these hinge members so as to press them inward against each other and cause them to lightly bind and hold the cigarettes between them and so prevent them from falling out after 110

having been placed therein. This tension is shown in the drawing as being provided by means of the bow springs 19 and 20 which are herein shown as engaging the lids 10 of the casing and also the outer edges of these holder members to act upon and keep them normally in closed position.

I have shown and described a pair of fluted hinged holder members, but any form of holder capable of positioning the cigarettes side by side so that their transverse major axes will set obliquely to the medial line lengthwise through the holder will fall within the spirit and scope of my invention.

15 I claim:

1. A cigarette case comprising a holder having a series of pockets oblong in cross-section for receiving and positioning a plurality of cigarettes, the transverse major axes of these pockets being parallel with each other and oblique with respect to the longitudinal medial line through the holder whereby the bodies of the cigarettes are caused to overlap each other.

2. A cigarette holder comprising a pair of holder members, a series of alternate grooves and ribs in one of said members for receiving and positioning the cigarettes and causing them to lie with their major axes parallel to each other and obliquely with respect to the medial line between said members whereby the bodies of the cigarettes lie side by side and overlap each other.

3. A cigarette holder comprising a pair of co-operating holder members, one of said members being provided with a series of grooves whose radii are greater than the shortest radius of the oblong cigarette whereby the cigarettes are caused to lie with their major transverse axes parallel to each other and obliquely with respect to the medial line between said members and their bodies to lie side by side and overlap each other.

4. In a cigarette holder, a pair of oppositely fluted holder members, the flutes in said opposite members being set staggering to cause the transverse major axes of the cigarettes held therein to lie parallel with each other and obliquely to the medial line between the holder members.

5. In a cigarette holder, a pair of oppositely disposed spring pressed fluted holder members hinged together, the flutes in said opposite members being staggered relative to each other to cause the transverse major axis of each to lie obliquely to the medial line between the holder members whereby their bodies are caused to over-lap each other.

In testimony whereof I affix my signature in presence of two witnesses.

HENRY D. MIX
